Primary Examiner — Lauren D McVey(74) *Attorney, Agent, or Firm* — Blank Rome LLP(57) **CLAIM**

The ornamental design for a portable cleanroom printing cabinet, as shown and described.

DESCRIPTION

FIG. 1 is a perspective view of a portable cleanroom printing cabinet showing my new design;

FIG. 2 is a left side view thereof;

FIG. 3 is a right side elevation view thereof;

FIG. 4 is a top plan view thereof;

FIG. 5 is a front elevation view thereof; and,

FIG. 6 is a rear elevation view thereof.

The dot-dash broken lines and evenly spaced broken lines depict environment and are for illustrative purposes only. The broken lines form no part of the claimed design.
